UNITED STATES PATENT OFFICE.

HENRY CURTIN, OF LITTLE FALLS, NEW YORK, ASSIGNOR OF ONE-HALF
TO WALLACE HOSE, OF SAME PLACE.

CIRCULAR-KNITTING MACHINE.

SPECIFICATION forming part of Letters Patent No. 380,385, dated April 3, 1888.

Application filed October 10, 1887. Serial No. 251,902. (No model.)

To all whom it may concern:

Be it known that I, HENRY CURTIN, of Little Falls, in the county of Herkimer, in the State of New York, have invented new and useful 5 Improvements in Circular-Knitting Machines, of which the following, taken in connection with the accompanying drawings, is a full, clear, and exact description.

This invention relates to the class of knitting-machines in which a tubular circular head is rotated on the bed-plate of the machine and carries on its periphery the knitting-needles in vertical positions. Said machines are designed for knitting cylindrical fabrics, and the 15 knitting of cylinders of different diameters requires needle-carrying heads of corresponding varying diameters. For this reason interchangeable needle-carrying heads of different sizes have been detachably connected to the 20 bed-plate and driving-gear.

My invention consists in an improved construction and combination of said parts, whereby by the same is simplified and the attachment and detachment of the needle-carrying head is 25 rendered more convenient and the wear of its journal-bearings is materially reduced, all as hereinafter fully described, and specifically set forth in the claims.

In the accompanying drawings, Figures 1 30 and 2 are partly side elevations and partly vertical transverse sections of needle-carrying heads of different diameters and their connection with the bed-plate and driving-gear embodying my invention.

35 A represents the bed-plate, which is usually mounted on standards or a suitable supporting-frame, not necessary to be here shown. Said bed-plate is provided with a circular eye, *e*, and with an annular rabbet, *a*, around the top edge of the eye. In said eye and rabbet are pivoted the head *D* and its driving-pinion *C* in the following manner: The said pinion *I* 40 form with an upward-projecting hub, *l*, which is journaled in the eye *e* and terminates flush with the base of the rabbet *a*, and upon the top 45 of the hub *l*, I mount the head *D*, which has its base fitted rotatably in the rabbet *a*. To protect the base of the head *D* from wear by fric-

tion on the base of the rabbet, I interpose between the base of said head and top of the hub 50 *l* a wear-plate or anti-friction metal ring, *b*, which also projects into the rabbet to serve as a bearing for the base of the head *D*.

By means of screws *t t*, passing vertically through the hub of the gear-wheel or driving-gear *C*, and through the wear-plate and into the wall of the head *D*, the head is firmly secured to the gear *C*, and the wear-plate clamped between them.

In connection with one and the same set of 60 bed-plate *A*, gear *C*, and wear-plate *b*, I employ interchangeable heads *D D*, of different sizes and with bases of uniform external diameters and corresponding screw-taps for the reception of the screws *t t*, which permit a 65 ready attachment and detachment of the interchangeable heads.

What I claim as my invention is—

1. The combination of the bed-plate *A*, provided with the eye *e*, and rabbet *a*, around the 70 top edge of the eye, the pinion *C*, formed with the upward-projecting hub *l*, journaled in the eye *e*, and the head *D*, seated upon the top of said hub and having its base fitted rotatably in the rabbet *a* and detachably connected to the 75 hub *l*, substantially as set forth.

2. The combination, with the bed-plate *A*, provided with the eye *e* and rabbet *a*, of the gear-wheel *C*, having the end of its hub flush with the base of the rabbet, the head *D*, detachably connected to the hub of the gear-wheel and having its base projecting into the rabbet *a*, and the wear-plate *b*, clamped between the end of the wheel-hub and base of the head and projecting into the aforesaid rabbet, 85 substantially as described and shown.

In testimony whereof I have hereunto signed my name, in the presence of two witnesses, at Little Falls, in the county of Herkimer, in the State of New York, this 6th day of October, 90 1887.

HENRY CURTIN. [L. S.]
